COMBINED TUNING CONTROL AND SPEAKER

Robert D. Kahn, Hewlett Harbor, N.Y., assignor to Fedtro, Inc., Rockville Centre, N.Y.

Filed May 11, 1964, Ser. No. 79,932

Term of patent 14 years

(Cl. D26—13)

FIG. 1

FIG. 2

FIG. 3

FIG. 4

FIG. 5

FIG. 1 is a front view of a combined tuning control and speaker showing my new design;

FIG. 2 is a side view thereof;

FIG. 3 is a rear view thereof;

FIG. 4 is a bottom view thereof;

FIG. 5 is a top view thereof;

FIG. 6 is a sectional view taken through lines 6—6 of FIG. 1; and

FIG. 7 is a sectional view taken through lines 7—7 of FIG. 1.

The speaker grille fragmentarily shown by groups of dots is continuous within the boundaries indicated.

I claim:

The ornamental design for a combined tuning control and speaker, substantially as shown and described.
